UNITED STATES PATENT OFFICE.

CHARLES L. VAN AMBURGH, OF LONG BEACH, CALIFORNIA.

RAZOR-STROPPING DEVICE.

Application filed November 11, 1926. Serial No. 147,798.

My invention relates to razor stropping devices which are incorporated in safety razors and in which the blade holder is adapted to be swung from one position to another at the end of each stropping movement, so that the opposite sides of the blade are acted on alternately.

It is a purpose of my invention to provide a stropping device in which the blade holder is operated in such a manner as to positively prevent the edge of the blade from cutting or injuring the strop or being injured by its engagement with the strop, thereby insuring the proper stropping of the blade.

It is also a purpose of my invention to provide a razor stropping device which is characterized by its simplicity of construction, easy mode of operation, and the readiness with which it can be cleaned after its use as a razor.

Another purpose is to provide a stropping device which eliminates the provision of hooks for retaining the blade in fixed position on the blade guard and the attendant disadvantages in shaving, and yet provides means by which the blade can be securely locked in position against the guard to prevent its accidental release during shaving.

I will describe only two forms of razor stropping device embodying my invention and will then point out the novel features thereof in the claims.

In the accompanying drawings,

Figure 1 is a view showing in side elevation and partly in section one form of razor stropping device embodying my invention, with parts thereof in one extreme position of movement and in applied position to a strop;

Figure 2 is a view similar to Figure 1, showing the parts in the other extreme position of movement;

Figure 3 is a view showing the stropping device in front elevation;

Figure 4 is an enlarged, fragmentary vertical section of the stropping device in the position shown in Figure 1;

Figure 5 is a horizontal sectional view taken on the line 5—5 of Figure 1;

Figure 6 is a horizontal sectional view taken on the line 6—6 of Figure 1 and showing the released position of the locking device embodied in the stropping device;

Figure 7 is a view similar to Figure 6, showing the locking position of the locking device;

Figure 8 is a view showing in side eleva-

tion another form of razor stropping device embodying my invention;

Figure 9 is a view similar to Figure 8, showing the stropping device in applied position to a strop;

Figure 10 is a view showing the razor stropping device of Figure 8 in front elevation;

Figure 11 is a plan of the stropping device shown in Figure 3, with a portion of the blade holder broken away to reveal parts not otherwise disclosed.

Similar reference characters refer to similar parts in each of the several views.

The razor stropping device shown in Figures 1 to 7, inclusive, comprises a frame having a base plate 15 formed of a single sheet of metal constructed to provide a blade guard 16 and a pair of upstanding ears 17 in which is fixed a friction shoe or bar 35 and in which is journaled a shaft 18. Fixed to the shaft between the ears is a blade holder 19 conventional in form in that it is adapted to slidably receive a blade 20 and to secure the blade against accidental removal by means of a projection 21, integral with the holder or with the shaft 18, and a rotatable collar 22, the projection and the collar fitting in respective recesses in the blade, as clearly illustrated in Figure 11. In order to prevent the use of any other blade in the stropping device when used as a razor, and thus to eliminate the use of blades of inferior quality, the blade holder 19 is provided with a pin 23 disposed between its jaws and adapted to repose in a recess 24 formed in the inner edge of the blade 20 and being preferably of V-shaped form, as illustrated in Figure 11. By the provision of the pin 23, blades not provided with a recess 24 cannot be inserted into the blade holder and, hence, cannot be used in the razor.

The shaft 18 has reduced extensions which project through the ears 17, and secured to these extensions are pinions 25 which constantly mesh with segmental gears 26 formed at the ends of a U-shaped yoke 27 which is secured to one end of a handle 28. By means of an arm 29—which is at one end pivotally secured on a pin 30 extending through a bifurcated block 31 fitted in the handle and is at its other end suitably secured to the base plate 15 of the frame, for instance, by riveting, as indicated at 33—the frame is adapted for an oscillatory movement relative to the handle 28. Thus, when the frame is oscillated, the pinions 25 are partially rotated to

and fro and thereby also cause the blade holder 19 to be alternately swung from one position to another relative to the base plate, the rotative movement of the blade holder being arrested by the engagement of the blade 20 with a razor strop 34, and the opposite sides of the blade being alternately acted upon by the strop when the device is applied thereto and moved to and fro thereon through the medium of the handle. Preferably, the pin 30 extends not only through the block 31 but also through the handle, although, of course, the pin may be fitted only in the block and the block may be driven into place for maintaining the pin in the required pivotal position. In either case the block provides a substantial support for the pin. At its end toward the frame the handle is preferably somewhat flattened and thereby transversely elongated, as indicated at 32, so as to allow a sufficient oscillatory movement of the arm within the handle for the required partial rotation of the pinions 25 by their engagement with the segmental gears 26. The arm 29 fits within the block 31 and within the flattened end of the handle in such a manner that, while it is allowed the required oscillatory movement, it is prevented from more lateral play than is necessary for the proper operation of the pinions by the segmental gears.

In the operation of the stropping device, the strop indicated at 34 is inserted between the base plate 15 and the friction shoe 35 connecting the ears 17. This friction shoe is preferably positioned so as to bend the strop slightly and thereby to insure a frictional contact of the strop with the frame, and the shoe is also in a position to hold the strop at the proper angle to the blade and to relieve the blade holder of friction at this point. By gripping the handle 28, the operator can now reciprocate the device on the strop so as to effect the stropping of the blade 20 in the following manner: As soon as the device is moved along the strop in the direction of the arrow in Figure 1, the segmental gears 26 actuate the blade holder and cause it to occupy the extreme position shown, in which the cutting edge of the blade 20 is trailing with respect to the direction of movement of the device, and the blade thus comes into a stropping engagement with the strop. The blade continues to occupy this position as long as the device is moved in the direction indicated. However, when the direction of movement of the device is reversed, the arm 29 rocks on the pivot 30 so that the pinions 25 are thereby forced by the gears 26 to rotate to the position shown in Figure 2, thus causing the blade holder 19 to swing to the other extreme position in which the cutting edge of the blade is in trailing relation to the direction of the movement of the handle, as indicated by the arrow in Figure 2. From the

foregoing it is clear that the strop's being held frictionally between the plate 15 and the shoe 35 causes the blade 20 to assume the trailing relation to the direction of either movements of the device along the strop, and the blade retains its position as long as no reverse movement of the device is attempted. It is also understood that, even when only the slightest reverse impulse is given to the handle 28, the frictional engagement of the strop with the frame causes the frame to resist the impulse. The blade is therefore immediately swung away from contact with the strop so that it is impossible for the blade even momentarily to assume a position in which its cutting edge is in the direction of the movement of the handle or of the device as a whole. It should be further observed that, owing to the frame's frictional engagement with the strop, a reverse movement of the frame upon the strop cannot be effected until by the handle's movement along the strop the blade also has been swung to its extreme reverse position. In other words, the swinging movement of the blade holder occurs before the frame is moved on the strop. Since thus the blade holder anticipates the movement of the frame, it is impossible at any time to cause the blade to cut into the strop by the movement of the device thereon. This is an important feature of my invention, as in stropping devices heretofore proposed the oscillating movement of the blade is accomplished by the handle's non-pivotal relation to the frame which carries the elements that effect oscillation. The best action possible would be instantaneous response, which because of the lost motion, results in tardiness, so that the cutting edge of the blade in such devices is allowed to remain in opposing contact with the strop for an instant, during which the strop is cut and the keen edge of the blade impaired.

It is important to note in regard to my device that the pressure, which the blade normally exerts on the strop as a result of the frame's resistance to a longitudinal movement of the device on the strop, may be further increased, if the operator increases the pressure of the frame on the strop, thereby effecting a superior stropping of the blade.

When using the stropping device as a razor, it is, of course, necessary to lock the arm 29 against movement relative to the handle 28 and in the positions shown in Figures 1 and 7, so that the blade will be held in the proper position relative to the teeth of the guard 16, as shown in Figure 3. For this purpose I provide a locking device which comprises a collar 36 rotatable on a head 37 fixed to or formed integrally with the arm 29 and provided with a groove 38 in which is movable one end of a wire 39, the wire embracing the collar, as clearly illustrated in Figure 5, so as to lock the collar to the head

and yet permit rotative movement thereof on the head. This collar is provided with a knurled disk or flange 40 adapted to be gripped by the fingers in rotating the collar to occupy either of two extreme positions. Extending from the disk 40 is a curved lip 41, and in one extreme position of the collar this lip is adapted to engage a companion lip 42 formed in the yoke-bearing end of the handle 28 and is thereby adapted to lock the handle 28 to the handle in the position shown in Figures 1 and 7. In the other extreme position of the collar, the lip 41 is rotated to the position shown in Figures 2 and 6, to which it disengages the lip 42 so as to permit the necessary movement of the arm relative to the handle and thereby effect oscillation of the blade holder.

It is important to note that, in the fixed position of the blade for shaving, hooked projections necessary in other stropping devices for holding the blade in shaving position are superfluous in my device. Thus, the objection is eliminated of the hooked projections contacting with the surface being shaved and thereby setting up a disagreeable abrasion. As shown in Figure 3, I provide projections 18^a, which extend just beyond the blade edge and serve as rests for the blade by engaging one side thereof so as to keep the blade at the proper distance from the guard 16, when the blade is held within the frame in a position for shaving, but do not project beyond the other side of the blade, and, hence, will not set up an abrasive action during shaving.

Referring now to Figures 8 to 10, I show another form of razor stropping device embodying my invention which is an adaptation of a conventional stropping device in that the frame 45 is provided with a blade guard 46 pivoted on ears 47 and including an operating extension 48 by which the guard can be moved to blade-engaging position, as shown in Figures 8 and 9, respectively. In the blade-engaging position of the guard, as shown in Figure 8, hooked extensions 49 engage the cutting edge of the blade at the ends in order to retain the blade in the proper position relative to the teeth of the guard so as to adapt the blade for shaving. In the disengaging position of the guard, as shown in Figure 9, the guard is swung away from the blade and toward the handle so as to permit the insertion into the frame of the conventional strop 34 in order to effect the stropping of the blade. By employing a pivoted guard, means for locking the frame against movement in respect to the handle is rendered unnecessary; otherwise, the stropping device is of the same construction as the device shown in Figures 1 to 7 and includes the friction she³⁵ shown in Figure 4. With the guard in the position shown in Figure 8, it will be manifest that the hooked extensions 49 prevent oscillating movement of the blade and,

hence, maintain the frame and the handle against relative movement, so that the blade is secured in position for shaving. It is clear that, when the blade is released by moving the guard to the position shown in Figure 9, ⁷⁰ the frame on the lever 29 can be swung on the pivot 30 and, by the engagement of the pinions 25 with the segmental gears 26, will effect oscillation of the blade holder during the stropping and in the precise manner as described in connection with the form shown in Figure 1, in order to prevent injury to the strop and the blade.

This form of stropping device is not so desirable as the form shown in Figure 1, ⁸⁰ because the operating extension 48 is so positioned that the operator may accidentally swing it toward the frame 45 during the use of the device in shaving and thereby unintentionally release the blade. ⁸⁵

Although I have herein shown and described only two forms of razor stropping devices embodying my invention, it is to be understood that various changes and modifications may be made therein without departing from the spirit of the invention and the spirit and scope of the appended claims. ⁹⁰

I claim as my invention:

1. In a razor stropping device, a support; a frame mounted in an oscillating relation to the support; a blade guard forming a part of the frame; means for frictionally engaging a strop in the frame; a shaft rotatably mounted in the frame; a blade holder secured on the shaft for rotation therewith and adapted to have its rotative movement arrested by the engagement of a blade therein with the strop; a pinion fixed on the shaft for oscillating the blade holder; and a segmental gear meshing with the pinion and being in a fixed relation to the support so that the pinion will be rotated by the segmental gear and will thereby cause the blade holder to oscillate and to swing the blade therein from one strop-engaging position toward another immediately upon an impulse given to the device for moving it longitudinally on the strop in the direction toward the blade's strop-engaging position. ¹⁰⁵

2. A razor stropping device, as embodied in claim 1, wherein the means for rotating the blade holder comprises segmental gears meshing with pinions, and wherein the frame is formed with a blade guard. ¹¹⁰

3. A razor stropping device comprising a frame having a blade guard; a blade holder mounted for rotation on the frame; a handle; an arm fixed to the frame and pivoted in the handle; a yoke on the handle, segmental gears on the yoke; and pinions connected to the blade holder and constantly meshing with the gears whereby when the handle is moved the gears will be actuated to rotate the pinions and thereby effect rotation of the blade holder. ¹²⁰ ¹²⁵ ¹³⁰

4. A razor stropping device, as embodied in claim 3, wherein the frame is provided with a blade guard on which a blade carried by the blade holder is adapted to repose in one extreme position of the blade holder; and co-acting means on the handle for locking the arm against movement relative to the handle in order to secure the blade holder in the aforementioned extreme position.
- 10 5. A razor stropping device, as embodied in claim 3, wherein the frame is provided with a blade guard on which a blade reposes when the blade holder is in one of its extreme positions; and a device for locking the arm against movement relative to the handle in order to retain the blade holder in the aforementioned extreme position, said device comprising a lip on the handle and a lip on the arm, and one of the lips being movable so as to engage or disengage the other.
- 15 6. A razor stropping device, as embodied in claim 3, wherein the frame is provided with a blade guard on which a blade reposes when the blade holder is in one of its extreme positions; and a device for locking the arm against movement relative to the handle in order to retain the blade holder in the aforementioned extreme position, said device comprising a lip fixed to the handle, and a lip 20 rotatable on the arm for engaging or disengaging the first lip.
7. A razor stropping device comprising a frame, a blade holder mounted for oscillation on the frame, a blade guard pivoted on the frame to occupy one position in which it is adapted to engage a blade carried by the holder to secure the blade against movement, and another position in which the blade is released so as to permit its oscillation by the holder in order to present first one side of the blade to a strop and then the other when the frame is reciprocated on the strop, and means for oscillating the blade holder before reciprocation of the frame and in such a manner that the blade is shifted from that side in which its cutting edge is leading to the other side in which its cutting edge is trailing and prior to a change in direction of movement of the frame, the said means comprising a handle, an extension on the frame pivotally secured to the handle for rocking movement, segmental gears carried by the handle, and pinions connected to the blade holder and meshing with said gears whereby, when the extension is rocked, the pinions will be actuated by the gears for rotating the blade holder, and wherein the frame is formed with a blade guard.
- 40 8. A razor stropping device comprising a frame having a blade guard, an actuator, means connecting the frame with the actuator to permit of relative oscillatory movements between the frame and said actuator, a blade holder mounted for rotation on the frame, means between the actuator and the blade holder for imparting rotation to the blade holder, a strop engaging shoe on the frame, the actuator adapted to be manually reciprocated on the strop while positioning the blade holder to establish proper contact of a blade with the strop, and the said shoe serving to insure frictional contact with the strop to hold the frame at rest for the interval of rotation of the blade holder that occurs at the beginning of each contemplated stroke.
- 15 9. A razor stropping device comprising a frame having a rotary blade carrying shaft and an arm fixed to extend from the frame, said frame formed with a blade guard, a strop-engaging friction shoe carried by the frame, a handle pivoted to the arm to permit the frame to be manually propelled over a strop with the shoe in contact therewith, and power transferring means between the handle and the blade holder, so that when the handle is actuated the frame is driven along the strop through the torque of the blade carrying shaft established by the resultant bellcrank action of its components and whereby, at the end of each stropping stroke, the frame is temporarily held at rest during the stroke changing interval and until the blade is turned completely over and represented in uniform contact with the strop preparatory to the propelling of the frame in an opposite direction.
- 20 10. A razor stropping device comprising a frame through which a strop is adapted to extend, a blade holder mounted for rotation on the frame to present first one side of a blade to the strop and then the other when the handle is reciprocated on the frame, and means for rotating the blade holder upon reciprocating of the handle and in such manner that the blade is shifted from that side in which its cutting edge is trailing prior to a change in direction of movement of the frame, the frame including a fixed arm and the said means for rotating the blade holder including a handle into which said arm extends and to which said arm is pivoted.
- 25 11. A razor stropping device comprising a frame, a blade holder mounted for rotation in either direction on the frame, and means for manually reciprocating the frame on a strop and for rotating the blade holder in one direction and then the other in such timed relation to the reciprocation of the frame that the blade carried by the holder is moved to a new position before initiation of movement of the frame and in a manner to constantly exert a torque on the blade holder to press the cutting edge of the blade against the strop, the frame including a fixedly supported long arm, and the said reciprocating means including a hollow handle in which the arm is pivoted for oscillation.
- 30 12. A razor stropping device comprising a frame, a blade holder mounted for rotation on the frame in either direction, and means

- for actuating the blade holder in a manner to utilize the torque of the blade holder when the blade carried thereby engages a strop to impart operating motion thereto along the 5 strop and whereby the blade anticipates the movement of the frame and thus properly positions itself before the contemplated movement of the frame, the said frame having a fixed arm extending therefrom and the said 10 actuating means including a hollow handle receiving said arm and to which the lower end of the arm is pivoted.
13. A razor stropping device comprising a frame, a blade holder mounted for oscillation 15 on the frame; a blade guard pivoted on the frame to occupy one position in which it is adapted to engage a blade carried by the holder to secure the blade against movement,
- and another position in which the blade is released so as to permit its oscillation by the 20 holder in order to present first one side of the blade to a strop and then the other when the frame is reciprocated on the strop, and means for oscillating the blade holder before reciprocation of the frame and in such a manner that the blade is shifted from that side in which its cutting edge is leading to the other side in which its cutting edge is trailing and prior to a change in direction of movement of the frame, the frame having a fixed long arm extending therefrom, and the oscillating means including a hollow handle in which the arm is supported at its lower end for rocking movement in two directions. 25 30

CHARLES L. VAN AMBURGH.
